UNITED STATES PATENT OFFICE.

LOUIS LANE, OF TOLEDO, OHIO, ASSIGNOR TO THE W. J. CLARK COMPANY,
OF SALEM, OHIO.

POST-CAP.

SPECIFICATION forming part of Letters Patent No. 714,199, dated November 25, 1902.

Application filed September 13, 1902. Serial No. 123,243. (No model.)

To all whom it may concern:

Be it known that I, LOUIS LANE, a citizen of the United States, residing at Toledo, Lucas county, Ohio, have invented certain new and 5 useful Improvements in Post-Caps, of which the following is a specification.

This invention pertains to improvements in post-caps employed in building construction in forming the junctures between posts and 10 horizontal timbers, and the invention will be readily understood from the following description, taken in connection with the accompanying drawings, in which—

Figure 1 is a perspective view of my improved post-cap; Fig. 2, a perspective view of the same shown upside down, and Fig. 3 a perspective view of the device shown in conjunction with timbers.

In the drawings, 1 indicates a post in conjunction with which a post-cap is to be used; 2, a second post setting upon the first one, as in case, for instance, where post 1 is employed in the basement and post 2 in the first story of a building; 3 and 4, horizontal timbers forming a juncture with and supported by post 1; 5, a gutter-shaped seat-piece resting on top post 1 and having its side walls engaging the sides of the horizontal timbers and the superpost 2; 6, a socket capping over the upper end of post 1; 7, flanges projecting upwardly from the side walls of the socket and secured, as by rivets, against the side walls of the seat-piece 5, the socket being formed of two halves having their juncture 20 near the transverse center of the seat-piece, each half having one of the upright flanges 7; 8, horizontal flanges projecting outwardly from the front and rear walls of the socket and riveted to the floor of the seat-piece; 9, 25 doweling-ribs secured to the floor of the seat-piece and designed to engage transverse grooves in timbers 3 and 4 to prevent endwise displacement of the timbers in the seat-piece; 10, bolt-holes through the side walls of the 30 seat-piece, and 11 holes through the front and rear walls of the socket.

It is to be understood that in the employment of my improved post-cap the superpost 2 will not always be present. For instance, where the post 1 is to aid in supporting a single floor only then superpost 2 will be absent and timbers 3 and 4 will have their ends abutting, and in cases the timbers 3 and 4 will be represented by a single continuous timber lying in the seat-piece. Bolts in the bolt-holes 55 of the post-cap may be employed in clamping the parts to the timbers and making the juncture more firm, and in case bolts are used through the side walls of the seat-piece and through the horizontal timbers lying in the 60 seat-piece then, of course, there is no need for the doweling-ribs 9.

The structure must be formed of wrought metal to give flexibility to the floor of the seat-piece and to the side walls of the socket. 65 The joint of separation between the two halves of the socket permits of the socket accommodating itself to such transverse flexure of the seat-piece as may be incident to its slight spreading to engage an enlarged timber or 70 its slight contraction to engage a somewhat smaller timber.

Each half of the socket is formed from a strip of plate metal cross-cut half across the plate where the corner bends are to occur. 75 The corner bends and flanged bends are then to be made and the flanges riveted to the seat-piece.

I claim as my invention—

In a post-cap, the combination, substantially as set forth, of a trough-shaped seat-piece, and a socket formed of two pieces having horizontal flanges secured under the floor of the seat-piece and having upwardly-extending flanges secured against the side walls 85 of the seat-piece.

LOUIS LANE.
